UNITED STATES PATENT OFFICE

HAYWOOD PARKER, OF ASHEVILLE, NORTH CAROLINA.

ATTACHABLE SEAT FOR WATER-CLOSETS.

No. 799,935.

Specification of Letters Patent.

Patented Sept. 19, 1905.

Application filed February 15, 1905. Serial No. 245,731.

To all whom it may concern:

Be it known that I, HAYWOOD PARKER, a citizen of the United States, and a resident of Asheville, in the county of Buncombe and 5 State of North Carolina, have invented a new and Improved Attachable Seat for Water-Closets, of which the following is a full, clear, and exact description.

At home and while traveling it is frequently 10 imperative that small children must occupy the seats of water-closets provided for adults, which is manifestly uncomfortable and to a certain extent dangerous, as a fall rearward might injure the spine of the child by striking 15 the same against the rear edge of the seat-opening.

The object of this invention is to provide a small portable seat-board having an opening of reduced diameter which may be instantly 20 placed in position upon the seat proper, be firmly held in place automatically, avoid the least injury to the water-closet, and be readily removable when not required for service.

The invention consists in the novel construction 25 and combination of parts, as is hereinafter described, and defined in the subjoined claims.

Reference is to be had to the accompanying drawings, forming a part of this specification, 30 in which similar characters of reference indicate corresponding parts in all the figures.

Figure 1 is a perspective view of a water-closet having the improvement applied upon the seat-board. Fig. 2 is a reversed plan view 35 of the improved attachable seat-board and securing means thereon. Fig. 3 is a plan view of the closet-seat and of the attachable seat-board, shown broken away for exposure of spring-fingers that are details of the securing 40 means; and Fig. 4 is a vertical longitudinal sectional view substantially on the line 4-4 in Fig. 1, showing the child's seat-board mounted and removably secured upon the stationary seat-board of the water-closet.

In illustrating the construction and application of the improvement, 5 represents the bowl of a water-closet of modern construction held vertically stationary on the floor of a toilet-room in the usual way for convenient 45 use. Upon the flat upper edge of the bowl 5 the apertured seat-board 6 is imposed and secured by suitable means and may have a cover 6^a hinged thereon, as shown in Fig. 1 and partially in Fig. 4.

7 indicates the improved seat-board, that in use is mounted upon the stationary seat-board

6 and detachably held thereon by means which will presently be described. The seat-board 7 may be formed of a wooden planchet having parallel sides and a suitable thickness and 60 marginal shape, preferably as represented in the drawings. The superficial area of the planchet or seat-board 7 is so proportioned that it will fully cover and overlap the edge of the opening *a*, formed in the stationary 65 seat-board 6, when the detachable seat-board is placed thereover. The normally front edge portion of the seat-board 7 is curved and may be semicircular, as appears in Figs. 2 and 3, this curved margin *b* being merged into the 70 straight edges *b'*, which extend rearward and end in a transverse edge portion *b*². The opening *c* in the seat-board 7 is of a proper diameter for its purpose and may be circular marginally, as shown. Near the rear edge 75 portion of the opening *c* a preferably metal reinforce-plate 8 is mounted transversely upon the normally lower side of the seat-board 7 and is thereto secured, this plate being preferably curved edgewise, as shown, and by its 80 position and manner of attachment serves as a batten-strip, preventing the board 7 from splitting. Upon the reinforce-plate 8, near each end thereof, the flattened ends of two resilient hook-bars 9 9 are respectively mounted 85 and secured as follows: As shown, each of the pair of spring hook-bars consists of a plate-like body portion having a flat end portion *d* attached upon an end of the reinforcing-plate 8 by screws or rivets. From the 90 portion *d* the plate-like bodies of the hook-bars 9 are curved laterally and toward each other, thus extending the free ends thereof toward each other, as shown in Figs. 2 and 3. A hook member *e* is formed on the free end 95 portion of each spring hook-bar 9, said hooks being bent downward and rearward and so disposed with regard to the opening *a* in the stationary seat-board 6 when the seat-board 7 is mounted thereon that the hooks *e* may be 100 passed below the lower rear edge of said opening and latched thereon, as shown in Figs. 3 and 4. Upon the lower side of the seat-board 7 at its transverse center and near the front edge a locking-finger 10 is placed, which may 105 be stationary, but preferably is adapted for a change in position toward or from the front edge of the seat-board. The finger 10 is of metal in rod form, extending down from a base-plate *g*, slotted longitudinally for the passage therethrough of a clamping-screw *h*, that may be manipulated by gripping the head 110

thereon and thus clamp the base-plate and finger at a suitable point. The relative position given to the finger 10 is such that when the hooks *e* have been engaged with the rear 5 lower edge of the seat-opening *a*, the seat-board 7 then inclining upward from rear to front, pressure applied upon the front edge of said seat-board will cause the spring hook-bars 9 to yield, so that the finger 10 may be 10 pressed down across the adjacent portion of the edge of the seat-opening *a* and hold the seat-board 7 seated upon the stationary seat-board 6. It will be seen that if the width of the seat-opening *a* from front to rear is such 15 that a proper pressure on the hook-bars 9 is not produced by the position given to the finger 10 the finger may be moved forward sufficiently to compensate for the looseness and put the spring-bars 9 under increased 20 tension, thus holding the seat-board 7 firmly upon the seat-board 6.

It will be noted that the supplementary seat-board 7 is quite light, is not bulky, can be readily carried in a suitable case for use when 25 traveling, and when applied renders any water-closet having an ordinary seat-board available for the safe and convenient accommodation of small children. Furthermore, it is obvious that the device is an excellent provision 30 for sanitary purposes and may by having an aperture of proper dimensions be carried and applied upon a public water-closet for the protection of adult persons against disease that might result from the use of the closet.

35 Minor changes in the proportion and form of details may be made, and all such changes are claimed that fall within the scope of the claims.

Having thus described my invention, I claim 40 as new and desire to secure by Letters Patent—

1. The combination with a water-closet bowl, and an apertured seat-board hinged thereon, of a supplementary seat-board having a smaller aperture therein, two resilient hook-bars on the supplementary seat-board, 45

and a depending finger on said seat-board, opposite said hook-bars, the hooks and finger engaging the edge of the aperture in the seat-board.

2. The combination with a water-closet seat-board having an aperture therethrough, of a supplementary seat-board having a smaller aperture therein, a reinforce-plate secured upon the normally lower side of the supplementary seat-board, resilient hook-bars 55 mounted at corresponding ends on the reinforcing-plate, and a depending finger on the lower side of the supplementary seat-board nearly opposite the hooks on the bars, these hooks and the finger having spring-pressed 60 contact with the edge of the aperture in the main seat-board when the supplementary seat-board is mounted thereon.

3. As an article of manufacture, a seat-board having an aperture therein, a pair of curved 65 resilient hook-bars secured on the lower side of said seat-board so as to project the hooks thereon away from the aperture, and a depending finger on the lower side of the seat-board forward of the aperture. 70

4. As an article of manufacture, a seat-board having an aperture therein, a reinforce-plate secured on the lower side of the seat-board rearward of the aperture, two similar resilient hook-bars secured by corresponding ends on 75 the reinforce-plate and spaced apart, said hook-bars being curved laterally and oppositely, a hook member bent rearwardly from the lower edge of each hook-bar at its free end, and a finger adjustably secured on the 80 lower side of the seat-board forward of the aperture therein.

In testimony whereof I have signed my name to this specification in the presence of two subscribing witnesses.

HAYWOOD PARKER.
